INVENTOR.
SOLOMON ABRAMS
BY *Joseph B. Gardner*
his ATTORNEY.

UNITED STATES PATENT OFFICE.

SOLOMON ABRAMS, OF HAYWARD, CALIFORNIA.

FOLDABLE BED.

Application filed June 22, 1925. Serial No. 38,691.

My invention relates to a foldable bed of the type adapted for concealment in a closet, buffet, or other receptacle, and from which it is arranged to be withdrawn when use of the bed is desired.

An object of the invention is to provide the bed with means which will cause the bed to be drawn into the receptacle when moved from extended to folded position.

Another object of the invention is to provide the bed with means which will cause the bed to be folded together when the bed is moved from without to within the receptacle.

A further object is to provide means carried by the bed for effectively and automatically closing the opening to the bed receptacle when the bed is properly positioned therein.

A still further object of the invention is to provide a bed of the character described which may be easily modified to provide a bed of the so-called roll-about type.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a vertical longitudinal sectional view of the bed in folded position within the receptacle.

Figure 2 is a view similar to Figure 1, excepting that the bed is shown extended for use.

Figure 3 is a fragmentary vertical transverse section of a side of the bed in extended position, the plane of the section being indicated by the line 3-3 of Figure 2.

Figure 4 is a view similar to Figure 1, showing the spring fabric and the upholstered mattress positioned therein.

Figure 5 is a sectional view of the bed modified for use as a roll-about.

In the embodiment of the invention as illustrated, the bed is arranged to be concealed within a receptacle 2, preferably in the form of a buffet. The bed 3 is of the general type shown in my Patent #1,525,433, granted February 10th, 1925, and comprises a plurality of connected bed-sections 4, 5

and 6, hereinafter respectively termed the foot section, the intermediate section, and the head section. Each of the sections is provided with rails 7, 8 and 9 respectively, 60 across which are stretched mattress-spring portions 10, 11 and 12, the intermediate portion being preferably additionally provided with coil springs 13.

Arranged to support the intermediate section directly upon the floor for movement to and from the receptacle is a carriage 14 provided with a plurality of rollers 16 so located as to properly support such section and any members carried thereby, in any position of the bed. The sections 4 and 6 are pivoted to the intermediate section adjacent the opposite ends thereof and are arranged in the inoperative position of the bed to lie perpendicularly disposed, as shown in Figure 1, or horizontally disposed in alignment with the section 5 when the bed is in operative position, as illustrated in Figure 2. A foot-board 17 and a head-board 18 are respectively positioned at the free ends of the sections 4 and 6, and are preferably pivotally connected so as to allow them to fold over the mattress 19 and hold the latter in position while the bed is folded.

Means are provided for guiding the bed into and out of the receptacle and for causing the head-section to properly fold and unfold accordingly. As here shown such means instead of being incorporated with the head-board as illustrated in my said patent, 90 is embodied in the structure entirely independent thereof, and simply comprises a link 21 connected to the end wall 22 of the receptacle and to the free end of the head section. By thus forming such means independent of the head-board a standard rather than special form of the latter may be used. The connecting point of the link and receptacle is preferably such that when the bed is extended the head section may lie horizontal and the link will be vertically disposed. In this manner the link may best function to properly guide the head section during the folding or unfolding of the bed and effectively assist in supporting such section while the bed is in use.

The foot-section 4 is assisted in being supported in the operative position of the bed by means of legs 23 which are pivoted to such section near the outer end thereof. 210 The legs are maintained in vertical position by means of a link 24 connected to the

leg and the carriage. Preferably positioned on the link 24 is a catch 26 which is arranged to releasably engage in an opening 27 of the foot rail 10 when the foot section is swung to the perpendicular position shown in Figure 1. Counterbalancing of the foot-section is here shown effected by means of a spring 28 attached to the carriage and to an extension 29 of the rail 10.

10 Means are provided for causing the bed, after being in its extended position, to move into the receptacle, and to a large extent complete its folding operation with little or no effort upon the part of the operator.

15 Such means includes a resilient member arranged for cooperation with the sections 5 and 6, and the force or energy for moving and folding the bed parts thereby, is stored therein during the preceding unfolding 20 movement of the bed and the withdrawal thereof from the receptacle. As here shown, the foregoing means comprises a rod 33 having one end 34 pivoted to the outer end of an extension 36 of the head-section rail 12 and slidably engaging in a slotted guide-piece 27 preferably fixed to the carriage and lying in a plane lower than the pivot of the sections 5 and 6. The extension projects beyond said pivot and is arranged to bear 30 under the rail 8 of the section 5 when the section 6 is horizontally aligned with the latter. Encircling the rod 33 and bearing at its opposite ends against the guide 37 and a collar 38 on the rod near the pivot, is a spring 39 of the compression type. With the bed in the extended position, as shown in Figure 2, the spring presses the extension 36 against the rail 8 and thus 35 serves to lock the intermediate and head sections in horizontal alignment. However, when it is desired to return the bed to the receptacle, it is given a slight shove toward the latter whereupon the head section will 40 be tilted upwardly and the spring 39 will be caused to exert its force in a direction to complete the folding movement of the head-section and consequently at the same time draw the intermediate section and foot-section into the receptacle, the latter section, it will be understood, being placed in the 45 desired folded relation either before or after other sections are moved into the receptacle.

50 Means are also attached to the bed structure for closing the opening to the receptacle when the bed is contained within the latter. As here shown, such means is in the form of a sectional closure and comprises closure sections 41, 42 and 43. The section 41, which as shown in Figure 1, is 55 arranged to cover the upper portion of the receptacle opening and is positioned at the outer end of the foot section 4 and fixed for movement with legs 23. The section 43 is 60 arranged to cover the base portion of the opening and incidentally forms the forward 65

70 wall of a drawer 44 supported in the carriage. The portion of the receptacle opening between the portions adapted to be covered by the sections 41 and 43, is arranged to be covered by the section 42 which is here 75 shown attached to the link 24. By means of vertically hinged side flaps 46, the cracks between the ends of the closure sections and the end walls of the receptacle may be effectively concealed when such sections are operatively engaged in the opening. It will 80 be clear that the closure sections may be readily designed to bring out any desired effect as to the apparent nature of the receptacle.

85 In Figure 5, I have shown how with a few slight modifications, the bed may be used as a roll-about. With the bed arranged for such use, casters 51 are preferably substituted for the rollers 16, and a leg mechanism 52 including legs 23' and links 24' similar to that provided for the foot-section, is also provided for the head section.

90 I claim:

95 1. In a foldable bed arranged to be connected to a relatively fixed object, a horizontally disposed bed section adapted for movement in a horizontal plane to and from said object, a second section pivotally connected to said first section and arranged to lie horizontally aligned or perpendicularly disposed with relation to said section, means connecting said second section to said object and arranged to guide said second section from one of said positions to the other upon horizontal movement of said first section, and means carried exclusively by the 100 bed and connected to one of said sections tending after folding of the bed has been 105 initiated to move said first section horizontally and place said first and second sections in angular relation.

110 2. A foldable bed arranged to be anchored to a relatively fixed object, comprising a bed section, means on which said section is supported for movement to and from said object in a horizontal plane, a second section pivoted to the first and arranged to be horizontally aligned therewith when said first section is moved outwardly from said object, means connecting said second section to said object whereby said section will be moved to angular relation to said first section when the latter is moved toward said object, and resilient means acting between said first and second sections and arranged to urge said first section toward said object upon the angular positioning of said sections.

115 3. A foldable bed arranged to be anchored to a relatively fixed object, comprising a bed section, means on which said section is supported for movement to and from said object in a horizontal plane, a second 120

section pivoted to the first and arranged to be horizontally aligned therewith when said first section is moved outwardly from said object, means connecting said second section to said object whereby said section will be moved to angular relation to said first section when the latter is moved toward said object, and resilient means arranged to urge said first section toward said object and lock 10 said sections in horizontal alignment when they are extended.

4. A foldable bed arranged to be anchored to a relatively fixed object, comprising a bed section, means on which said section is supported for movement to and from said object in a horizontal plane, a second section pivoted to the first and arranged to be horizontally aligned therewith when said first section is moved outwardly from said object, means connecting said second section 20

to said object whereby said section will be moved to angular relation to said first section when the latter is moved toward said object, said second section having an extension projecting beyond its pivot arranged 25 to underlie the top surface of said first section when the sections are horizontally aligned, a rod pivotally connected at an end to said extension, a guide for said rod fixed to said first section, and a spring encircling 30 said rod interposed between said guide and the pivoted end of the rod, the guide being so positioned that as the second section moves to horizontal position the rod first comes into alignment with that section and 35 then moves out of alignment.

In testimony whereof, I have hereunto set my hand at Oakland, California, this 15th day of June, 1925.

SOLOMON ABRAMS.
